UNITED STATES PATENT OFFICE.

WILLIAM A. HANNA, OF HENRY, ILLINOIS.

WAGON-STAKE.

SPECIFICATION forming part of Letters Patent No. 246,308, dated August 30, 1881.

Application filed July 11, 1881. (No model.)

To all whom it may concern:

Be it known that I, WILLIAM A. HANNA, of Henry, in the county of Marshall, in the State of Illinois, have invented an Improved Wagon-Stake; and I do hereby declare that the following is a full, clear, and exact description thereof, reference being had to the annexed drawings, making a part of this specification, in which like letters of reference refer to like parts, 10 and in which—

Figure 1 represents a side view, Fig. 2 edge view, Fig. 3 sectional top view, through $x x$.

H is one end of the wooden bolster of a freight or farm wagon.

15 My wagon-stake consists, primarily, of one long bent strip of flat bar-iron, A , and one bent strip of strap-iron, B .

So far as I know there has never been constructed before this a wagon-stake entirely of 20 wrought-iron.

The strip of bar-iron A is straight from A to A^2 , at which latter point it is bent to a curve of about three-fourths of an inch radius, and is again made straight and parallel to said 25 other part A A^2 , from said curved part A^2 to the point A^3 . From A^3 to A^4 it is bent off at an angle of about thirty-five degrees, to serve as a brace. To fasten this strip of bar-iron A to the bolster I bend the end A' in at right angles to the vertical part A A^2 , and put the bolt F through it and said bolster. The other end, A^5 , I also bend in parallel with the bolster and put through it and said bolster the bolt K . To further brace this stake I prolong the end 30 A^6 and bend it up to A^6 . At this latter point, A^6 , I flatten it edgewise till it is thick enough to receive the rivet R' and narrow enough to come between the two parts of the bent strip of strap-iron B at that point.

40 In my plans which I had filed as a caveat in last March the end A^6 was welded to the inside of the part between A and A^2 of the strip of bar-iron; but my new way I regard as both cheaper and stronger. In said caveat the end

45 A A' was also attached in a different way to the bolster. I then hammered said end out into a bolt; but that was a much harder way than my present one.

The strip of strap-iron B is bent as shown in Fig. 2 at B^3 , from which point to B^2 and B^4 it 50 is straight, and fits in grooves G , about three thirty-seconds of an inch deep, made in the inside of the strip of bar-iron A , (shown in cross-section in Fig. 3, and also in Fig. 2 by the dotted lines from B^2 up to B^3 and down to B^4 .) 55 This strip B is secured to the bar-iron A by being pressed into said grooves G and held by the bolts D D . It is fastened to the bolster H by the bolt E through its ends B' and B^5 . The slanting parts B' B^2 and B^4 B^5 serve as side 60 braces to the stake.

The stake-rings C C are also made of narrow strap-iron, bent as shown in Fig. 3, and secured to the stake by the rivets R R' . This riveting is not done so tightly as to prevent the rings 65 C from being turned down against the stake, and yet is snug enough to prevent any rattling. These rivets R R' also help to hold the strap-iron B in place, even should the bolts D D get loose. 70

The space between B^3 and A^2 serves as an eye to attach a rope or chain to.

This wagon-stake is used the same as is the ordinary wooden one.

What I claim as my invention, and for which 75 I desire Letters Patent, is as follows, to wit:

1. As a wagon-stake, the strip of bar-iron, straight from A to A^2 and from A^2 to A^3 , curved at A^3 , and bent off at an angle from A^3 to A^4 , with grooves G G , and having its ends fastened to the bolster H , in combination with the strip of strap-iron B , bent as shown, and having its ends bolted to the bolster H . 80

2. The strip of bar-iron A , with grooves G G , bent ends A' and A^6 , with bolts F and K , 85 the strip of strap-iron B , with bolts E and D D , and stake-rings C C' , with rivets R R' , in combination with the bolster H , substantially as and for the purpose specified.

In testimony that I claim the foregoing invention I have hereunto set my hand this 90 27th day of June, 1881.

WILLIAM A. HANNA.
